COMBINED HOSIERY WASHER AND SUPPORT THEREFOR

Pinckney F. Fleming, Houston, Tex.

Application May 27, 1957, Serial No. 46,363

Term of patent 14 years

(Cl. D49—2)

Fig. 1

Fig. 3

Fig. 1 is a side elevational view of a combined hosiery washer and support therefor showing my new design;

Fig. 2 is a front elevational view of the combination; and

Fig. 3 is a top plan view thereof.

I claim:

The ornamental design for a combined hosiery washer and support therefor, as shown.
